INK APPLICATOR FOR TYPEWRITER RIBBONS

Filed June 18, 1947

UNITED STATES PATENT OFFICE

2,588,548

INK APPLICATOR FOR TYPEWRITER
RIBBONS

Orland W. Markes, Detroit, Mich.

Application June 18, 1947, Serial No. 755,522

9 Claims. (Cl. 118—260)

1

My invention relates to a new and useful improvement in an ink applicator for writing ribbons which are wound onto a reel and wound off of a reel and adapted to pass before type which make the impression through the ribbon. This type of ribbon is commonly used on various writing machines, such as, calculating machines, adding machines, bookkeeping machines, typewriters, etc.

It is an object of the present invention to provide an ink applicator of this class which will be simple in structure, economical of manufacture, durable, compact, easily and quickly installed and highly efficient in use.

Another object of the invention is the provision in an ink applicator of this class of a reservoir having a closure for its open end and provided with a filling opening inwardly from its open end so that as the closure is raised outwardly sufficiently to clear the filling opening, the reservoir may be filled while the closure is still in closing position.

Another object of the invention is the provision in an ink applicator of this class of an applying wick extended through a passage or tube of slightly larger inside diameter than the outside diameter of the wick and provided with means on its inner end for preventing spilling or leakage of ink outwardly around the wick.

Another object of the invention is the provision in an ink applicator of this class of a reservoir and a closure or stopper therefor so constructed and arranged that entry of air into the reservoir may be readily obtained, thus, facilitating the flow of ink and, also, facilitating the filling of the reservoir in that the air within the reservoir may be permitted to escape.

Another object of the invention is the provision in an ink applicator of this class of a retainer or holder so constructed and arranged that it will bear against the reservoir at separated points to facilitate easy rotating of the reservoir in its retainer.

Another object of the invention is the provision in an ink applicator of a reservoir rotatably mounted and having a stopper mounted therein which is rotatable relatively thereto and with which the wick at the applying point will also rotate.

Another object of the invention is the provision in an ink applicator of this class of a wick supporting tube having its end terminating flush with the end of the wick and cut on a diagonal to expose a portion of the wick for applying purposes.

Another object of the invention is the provision

2

in an ink applicator of a reservoir and a stopper so arranged and constructed that the reservoir may be moved vertically and adjusted to various positions and the stopped itself which carries the applying wick may also be moved vertically relatively to the reservoir, thus affording two means of vertical adjustment.

Another object of the invention is the provision in an ink applicator of a reservoir formed from transparent material and having a liquid level indicator thereon so that the user may, through visual inspection, determine the quantity of ink contained within the reservoir.

Another object of the invention is the provision in an ink applicator of this class of means for engaging and limiting the spout of a filling tube when inserted through the opening formed in the reservoir.

Other objects will appear hereinafter.

It is recognized that various modifications and changes may be made in the detail of structure illustrated without departing from the invention and it is intended that such shall be embraced within the scope of the claims which form a part hereof.

Forming a part of this specification are drawings in which:

Fig. 1 is a fragmentary, perspective view of a machine showing the invention applied.

Fig. 2 is a side elevational view of the invention,

Fig. 3 is a rear elevational view of the invention,

Fig. 4 is a side elevational view of the invention showing the parts in separated relation,

Fig. 5 is a longitudinal, central, sectional view of the invention showing the stopper moved to position to permit filling of the reservoir,

Fig. 6 is an enlarged sectional view taken on line 6—6 of Fig. 5,

Fig. 7 is an enlarged sectional view taken on line 7—7 of Fig. 3,

Fig. 8 is an enlarged sectional view taken on line 8—8 of Fig. 2,

Fig. 9 is a fragmentary, elevational view of a slight modification,

Fig. 10 is a fragmentary, elevational view of a slight modification of a wick used in the invention.

In the drawings, I have indicated a supporting arm 11 having the angularly turned portion 12 at its lower end provided with an opening 13 through which a screw may be projected for fastening the supporting arm to a suitable support on a machine which used. Carried by the upper end of the supporting arm is a pair of semi-circular resilient gripping members 14 and 15,

each of which is pressed inwardly to provide a bead or tit 16 which bears against a reservoir 17. This reservoir is preferably formed from transparent plastic or any other suitable transparent material so that the quantity of ink in the reservoir may always be ascertained by visual inspection, the space 38, between the members 14 and 15, affording sufficient space for inspecting purposes. Formed on this reservoir is a line 18 which indicates the normal ink level of the reservoir. This reservoir is provided with a lateral opening 19 adjacent its upper end.

A stopper is provided embodying the portion 20 which extends inwardly of the open end of the reservoir and when fully closed extends beyond the opening 19. This stopper 20 is provided at its upper end with a flange 21 which is slightly smaller than the outside diameter of the reservoir so that the reservoir may be lowered in the retaining members 14 and 15 to a position where the upper face of the cap is extended below the upper edges of the members 14 and 15. Fixed to and projecting downwardly from the stopper 20 is a tube 22 having the lateral opening 23 formed therein. This tube 22 is in alignment with the bore 39 formed through the stopper 20. Fixed to and projecting upwardly from and thence laterally turned relatively to the stopper 20 is a wick supporting tube 26. The bore 39 and the tube 22, as well as the tube 26, is of a larger inside diameter than the outside diameter of the wick 24 which is extended therethrough. Consequently, there is a space around the wick, as clearly appears in Fig. 8, excepting at its lower end which is provided with a pad 25 of cotton batting or other suitable material which serves to entirely fill the tube 22 so as to prevent leakage of ink through this space. This packing 25 is positioned below the opening 23. The wick, at its outer end, terminates flush with the end of the tube 26 and the end of the tube 26 is diagonally cut away at one side as at 27 to expose one side of the wick 28 which may be brought into engagement with the inking roller 29. The wick, at the cut away portion 27 and at which the applying portion 28 appears, is fused or glued to the end of the tube 27.

In use, the device is mounted on the machine with which used and the reservoir or the stopper 20 vertically adjusted to the proper position so that the exposed portion 28 of the wick may engage against the inking roller 29 against which travels one face of the ribbon 30 which unwinds from the reel 31 and which passes in contact with the guide rollers 32 and 33. Experience has shown that by properly inking the roller in this manner a more desirable form of writing is obtained and, particularly, the one which is more clearly legible. Experience has also shown that the life of the ribbon is greatly prolonged by maintaining the same in a properly inked condition.

The reservoir may be rotated in the members 14 and 15 and slid vertically and while this reservoir is firmly held in position, due to the fact that only separated points bear against the reservoir, a free and easy moving is thus made possible. By moving this stopper 20 upwardly and downwardly while it is functioning as a stopper of the reservoir, vertical adjustment may thus be effected independently of the vertical adjustment of the reservoir itself. The stopper also is rotatable relatively to the reservoir so that there is thus provided a pair of means for rotative ad-

justment as well as a pair of means for vertical adjustment.

When it is desired to re-fill the reservoir with ink, the stopper is raised until the inner end 5 clears the opening 19 formed in the reservoir and the spout of the ink containing can or bottle may then be inserted through the opening 19. When in this position, the tube 22 protects the wick 24 and prevents it from coming into contact with the spout of the ink containing can or bottle and thus being broken. The opening 23 serves as a bleed opening for the air so that an easy filling of the reservoir thus becomes possible even while the closure or stopper 23 is functioning as a closure.

15 In this way, a spilling of ink is avoided. By having the clearance around the wick, the free travel of the air for filling purposes is made possible. Experience has also shown that this clearance around the wick affords an easier flow of ink 20 out to the inking portion 28 of the wick. It is believed obvious that the fit of the stopper 20 and the reservoir is a snug one so as to prevent leakage between the stopper and the reservoir when the stopper is in closing position.

25 In Fig. 9, I have shown a slight modification in which the tube 26a corresponds to the tube 26. Mounted on the end of the tube 26a is a collar 44 having the yoke arms 45 and 46 between which is rotatably mounted a roller 47 which is contacted by the end 28a of the wick. This structure is adapted for use where a machine with which used is not provided with the roller 29, shown in Fig. 1, so that the roller 47 would contact directly against the ribbon 30.

30 35 In Fig. 10, I have shown a modification of a wick 24a having the ends split to provide the separated portions 48 and 49 so that a heavier inking of the roller, which is contacted by the wick, may be effected.

40 What I claim as new is:

1. An ink applicator of the class described, comprising: a reservoir adapted for the reception of ink and having one end closed and the other end open and provided with a lateral opening adjacent its open end; a stopper inserted into said open end for closing the same and adapted, upon being thrust inwardly a predetermined distance, for covering said lateral opening and, upon being drawn outwardly for uncovering said lateral opening while serving as a closure for the open end of said reservoir, said stopper having a passage formed therethrough; a tubular member projecting outwardly from the outer end of said stopper and communicating with said passage; and a wick extended through said tubular member and through said passage and projecting beyond the inner end of said stopper into said reservoir; and a tubular member projecting inwardly beyond the inner end of said stopper and embracing said wick and serving as a protection therefor against articles inserted through said lateral opening upon movement of said stopper to lateral opening uncovering position, the outside diameter of said wick being less than the inside diameter of said tubular member and said passage; and means mounted in the inner end of said second named tubular member around said wick for closing the space between said wick and said tubular member.

70 2. An ink applicator of the class described, comprising: a reservoir adapted for the reception of ink and having one end closed and the other end open and provided with a lateral opening adjacent its open end; a stopper inserted into said open end for closing the same and adapted,

upon being thrust inwardly a predetermined distance, for covering said lateral opening and, upon being drawn outwardly for uncovering said lateral opening while serving as a closure for the open end of said reservoir, said stopper having a passage formed therethrough; a tubular member projecting outwardly from the outer end of said stopper and communicating with said passage; and a wick extended through said tubular member and through said passage and projecting beyond the inner end of said stopper into said reservoir; and a tubular member projecting inwardly beyond the inner end of said stopper and embracing said wick and serving as a protection therefor against articles inserted through said lateral opening upon movement of said stopper to lateral opening uncovering position, the outside diameter of said wick being less than the inside diameter of said second mentioned tubular member and said passage; and means mounted in the inner end of said second named tubular member around said wick for closing the space between said wick and said tubular member, said second named tubular member having a lateral opening formed therein between the inner end of said stopper and space closing means for establishing communication between the interior of said reservoir and the space in said passage and first named tubular member which surrounds said wick.

3. An ink applicator of the class described, comprising: a transparent reservoir adapted for the reception of ink, one end of said reservoir being open; a stopper for said open end of said reservoir slidably inwardly of said reservoir and rotatable relatively thereto; a wick projecting through said stopper and carried thereby and movable in unison therewith and projecting at its inner end beyond the inner end of said stopper and extending into said reservoir and extending at its outer end beyond the outer of said stopper; an enclosing sheathing for enclosing the major portion of the outer end of said wick and extending radially outwardly from said stopper; a pair of spaced apart supporting members for embracing said reservoir at spaced apart points for supporting the same, said reservoir being rotatable and longitudinally movable in said supporting member, said supporting members being spaced apart sufficiently for visual inspection of said reservoir.

4. An ink applicator of the class described, comprising an ink containing reservoir open at one end; a stopper for said open end and insertible into the open end of said reservoir and movable inwardly and outwardly thereof and rotatable relatively thereto, said stopper having a passage formed therethrough; a wick projected through said passage and extending beyond opposite ends of said stopper; an enclosing sheathing for the outer end of said wick and extending radially outwardly from said stopper; a collar mounted on said sheathing; a rotatable roller carried by said collar and contacting the outer end of said wick.

5. An ink applicator of the class described, an ink containing reservoir open at one end; a stopper for closing said open end and having a passage formed therethrough; a wick projected through said passage and extending beyond opposite ends of said stopper; a tubular member for enclosing the outer end of said wick and extending radially outwardly of said stopper and being rotatable relatively to said reservoir, said outer

end of said wick being secured to the tubular member adjacent its end.

6. In an ink applicator of the class described, an ink containing reservoir open at one end; a stopper for closing said open end and having a passage formed therethrough; a wick projected through said passage and extending beyond opposite ends of said stopper; a tubular member for enclosing the outer end of said wick and extending radially outwardly of said stopper and being rotatable relatively to said reservoir, said outer end of said wick being secured to the tubular member adjacent its end, said tubular member being diagonally cut at the end at which said wick is secured for exposing a portion of the length of said wick.

7. In an ink applicator of the class described, an ink containing reservoir open at one end; a stopper for closing said open end and having a passage formed therethrough; a wick projected through said passage and extending beyond opposite ends of said stopper; a tubular member for enclosing the outer end of said wick and extending radially outwardly of said stopper and being rotatable relatively to said reservoir, said outer end of said wick being secured to the tubular member adjacent its end, said tubular member being diagonally cut at the end at which said wick is secured for exposing a portion of the length of said wick; a tubular member carried by said stopper for enclosing a portion of the wick projecting inwardly of the inner end of said stopper, said passage and said tubular members being of larger inside diameter than the outside diameter of said wick to provide a space between the same and said wick, said second named tubular member having an opening formed therein for establishing communication of said space with the interior of said reservoir.

8. In an ink applicator of the class described, an ink containing reservoir open at one end; a stopper for closing said open end and having a passage formed therethrough; a wick projected through said passage and extending beyond opposite ends of said stopper; a tubular member for enclosing the outer end of said wick, said outer end of said wick being secured to the tubular member adjacent its end, said tubular member being diagonally cut at the end at which said wick is secured for exposing a portion of the length of said wick; a tubular member carried by said stopper for enclosing a portion of the wick projecting inwardly of the inner end of said stopper, said passage and said tubular members being of larger inside diameter than the outside diameter of said wick to provide a space between the same and said wick, said second named tubular member having an opening formed therein for establishing communication of said space with the interior of said reservoir; and means for closing said space adjacent the inner end of said second named tubular member.

9. An ink applicator of the class described, comprising: a reservoir open at one end and adapted for reception of ink; a stopper for said open end movable inwardly and outwardly thereof, said reservoir having a filling opening adjacent its open end, said stopper, upon being moved inwardly a pre-determined distance, covering said opening and upon being moved outwardly a pre-determined distance uncovering said opening while serving as a stopper for the open end of said reservoir, said stopper having a passage formed therethrough; a wick projected through

said passage and extended beyond opposite ends of said stopper; a tubular member carried by said stopper and enclosing the wick projecting beyond the outer end of said stopper; a tubular member carried by the inner end of said stopper and enclosing a portion of the wick extending beyond the inner end of said stopper and covering the portion of said wick extending beyond the lateral opening in said reservoir upon movement of said stopper to uncovering position, the outside diameter of said wick being less than the inside diameter of said tubular members and said passage to provide a space therein surrounding said wick, said second named tubular member having a lateral opening therein for establishing communication between said space and the interior of said reservoir; and means in said second named tubular member for closing said space therein below the lateral opening formed in said second named tubular member.
